UNITED STATES PATENT OFFICE.

ISIDOR J. KUSEL, OF CHICAGO, ILLINOIS, ASSIGNOR TO STRONGHART COMPANY, OF CHICAGO, ILLINOIS, A CORPORATION OF ILLINOIS.

COIN BANK.

Application filed January 5, 1920. Serial No. 349,467.

To all whom it may concern:

Be it known that I, ISIDOR J. KUSEL, a citizen of the United States, residing at Chicago, in the county of Cook and State of Illinois, have invented a certain new and useful Improvement in Coin Banks, of which the following is a full, clear, concise, and exact description, reference being had to the accompanying drawings, forming a part of this specification.

My invention relates to coin banks for receiving and holding coins, particularly for savings purposes.

One of the objects of the invention is to provide a locking means for coin banks by which the bank may be effectively locked but readily opened by an authorized person to remove the deposited coins.

Another object of the invention is to provide such a locking arrangement which can be readily operated by means of a small key.

Another object of the invention is to secure simplicity of construction and effectiveness of operation.

Another object of the invention is to secure the foregoing and other desirable results in a practical and effective manner.

In the accompanying drawings Fig. 1 is an edge view of a coin bank embodying my present invention;

Figs. 2 and 3 are plan views of the separable members of which the bank is composed separated from one another; and

Fig. 4 is a cross section on an enlarged scale showing the parts in assembled and locked relation.

Fig. 5 is a front elevation view of the key.

In the drawings I show a bank A preferably of a substantially circular form, as shown in Figs. 2 and 3. The bank is made of two separable members 1 and 2, the former of which comprises the top 3 and a circular side wall or flange 4, and the latter of which comprises the bottom 5 and another wall or flange 6 adapted to fit outside of the wall or flange 4 so as to permit the two parts to fit telescopically together.

The wall 6 is provided with inwardly projecting pins 7, 8 and 9, and the wall 4 with bayonet slots 10, 11 and 12, adapted to receive the pins 7, 8 and 9, respectively. By means of these pins and walls the two separable members 1 and 2 may be interlocked by inserting the pins in the bayonet slots and then turning the two members relatively

to one another a slight distance, as permitted by the elongated or laterally extending end portions of said slots.

As a means for holding said separable members 1 and 2 in position interlocked by said bayonet walls, a locking arrangement is provided which will hold said two members against relative rotation and so will hold them interlocked by means of said slot and pins. An arrangement shown consists of a pivoted lever 13, pivotally mounted on the wall 4 by means of a pivot 14 and provided with an abutment 15 which is adapted to engage a stop or shoulder 16 on the bottom 5. When the abutment or shoulder 15 engages the shoulder or stop 16 the separable members of the bank are effectively locked together because relative rotation such as necessary to permit their separation by the bayonet slots is prevented. A spring 17 secured to the top 3 normally acts upon the upper side of the lever 13, (Fig. 4) and tends to hold said lever 13 in a downward position in which the shoulder 15 will engage the shoulder 16. This tends to maintain the bank always in a locked condition.

The bank may be unlocked by swinging the lever 13 against the opposition of the spring 17 so that the shoulder 15 will come out of engagement with the shoulder 16. This may be accomplished by means of a key 18 adapted for insertion in a keyhole 19 in the wall 6. The key 18 is provided with a projection 18^a, which is adapted to act against an end portion 20 of the lever 13 and thereby tilt said lever, swinging the end portion 20 down (Fig. 4) and the other end portion up, and thereby raising the shoulder 15 from engagement with the shoulder 16, and unlocking the bank, allowing it to be opened by merely turning the two separable members relatively to one another and then separating them by means of the bayonet slots and pins.

A guard or shield 21 is preferably provided to prevent the lever 13 from being interfered with by coins. This member 21 is preferably a plate-like member having substantially the curvature of the wall 6 and extending substantially parallel with said wall throughout its length, as shown in Fig. 3. It is preferably secured to the bottom 5 by means of rivets 22. Said member 21 is provided with an aperture 23 to receive the end of the key 18 when the latter is inserted.

through the keyhole 19. By this arrangement the locking mechanism of the bank may be easily actuated without any danger of interference from coins, which is particularly desirable when the bank is pretty well filled.

The pins 7, 8 and 9 are not separated from one another by equal distances, but by unequal distances, as for example by putting 10 the pins 7 and 8 closer together than either one of said pins is situated with reference to the pin 9. In this way it will be necessary to put the separable parts of the bank together in proper relationship, because said 15 pins will not cooperate with their slots until proper registration is effected. Furthermore, the bank may be very easily and quickly closed and locked.

It will be understood that changes and 20 modifications may be made without departing from the spirit of the invention.

What I claim is:

1. A coin bank having separable members provided with bayonet slot interlocking devices, and means for holding said members against unlocking movement comprising a lever on one member provided with a shoulder and a cooperating shoulder on the other member, the shoulders being in operative engagement only when said bayonet devices are in their extreme interlocked position.

2. A coin bank having separable members provided with bayonet slot interlocking devices, and means for holding said members against unlocking movement comprising a lever on one member provided with a shoulder and a cooperating shoulder on the other member, and spring means for holding said lever normally in position to cause the engagement of said shoulders with one another, said shoulders being operatively engageable only when the bayonet devices are interlocked.

3. A coin bank having separable members provided with bayonet slot interlocking devices, and means for holding said members against unlocking movement comprising a lever on one member provided with a shoulder and a cooperating shoulder on the other member, said shoulders being operatively engageable only when the bayonet devices are interlocked, spring means for holding said lever normally in position to cause the engagement of said shoulders with one another, and means for actuating said lever in opposition to said spring to release said shoulders from one another.

4. A coin bank having separable members provided with bayonet slot interlocking devices, and means for holding said members against unlocking movement comprising a lever on one member provided with a shoulder and a cooperating shoulder on the other member, said shoulders being operatively engageable only when the bayonet devices

are interlocked, spring means for holding said lever normally in position to cause the engagement of said shoulders with one another, and means for actuating said lever in opposition to said spring to release said shoulders from one another, said means comprising a key adapted for insertion through an aperture in the wall of the bank and adapted to engage and operate said lever.

5. A coin bank having separable members 75 provided with bayonet slot interlocking devices, and means for holding said members against unlocking movement comprising a lever on one member provided with a shoulder and a cooperating shoulder provided on the other member by an inturned portion of one of the walls thereof, and spring means for holding said lever normally in position to cause the engagement of said shoulders with one another, said shoulders 80 being operatively engageable only when the bayonet devices are interlocked.

6. A coin bank having separable members provided with bayonet slot interlocking devices, and means for holding said members against unlocking movement comprising a lever on one member provided with a shoulder and a cooperating shoulder on the other member, and spring means for holding said lever normally in position to cause the engagement of said shoulders with one another, said cooperating shoulder being provided by an inturned portion of one of the walls of the second mentioned member, and said lever being formed with a downwardly 95 projecting portion, the end of which provides the shoulder for engaging said other shoulder.

7. A coin bank having separable members provided with bayonet slot interlocking devices, and means for holding said members against unlocking movement comprising a lever on one member provided with a shoulder and a cooperating shoulder on the other member, and spring means for holding said lever normally in position to cause the engagement of said shoulders with one another, said cooperating shoulder being provided by an inturned portion of one of the walls of the second mentioned member, said lever having a projecting end portion providing a surface for said key.

8. A coin bank having separable members provided with bayonet slot interlocking devices, and means for holding said members against unlocking movement comprising a lever on one member provided with a shoulder and a cooperating shoulder on the other member, and spring means for holding said lever normally in position to cause the engagement of said shoulders with one another, in combination with a guard forming a wall on the inner side of said lever.

9. A coin bank having separable members provided with bayonet slot interlocking de-

vices, and means for holding said members against unlocking movement comprising a lever on one member provided with a shoulder and a cooperating shoulder on the other member, and spring means for holding said lever normally in position to cause the engagement of said shoulders with one another, in combination with a guard forming a wall on the inner side of said lever, said 10 wall comprising a plate-like member secured to the floor of the bank.

10. A coin bank having separable members provided with bayonet slot interlocking devices, and means for holding said mem-

bers against unlocking movement comprising a lever on one member provided with a shoulder and a cooperating shoulder on the other member, said shoulders being operatively engageable only when the bayonet devices are interlocked, said bayonet slot device being located at unequal distances from one another to insure closure of the bank with the operating devices in proper position.

In witness whereof, I hereunto subscribe 25 my name this 12th day of December, A. D., 1919.

ISIDOR J. KUSEL.
